CUTAWAY DOOR WINDOW CONSTRUCTION

Filed Dec. 8, 1930

UNITED STATES PATENT OFFICE

2,060,862

CUTAWAY DOOR-WINDOW CONSTRUCTION

Otto F. Graebner, Detroit, Mich., assignor to The Murray Corporation of America, a corporation of Delaware

Application December 8, 1930, Serial No. 500,700

11 Claims. (Cl. 296—48)

This invention aims to utilize, in car doors, windows whose forward and rear edges are parallel except as to an upper portion of the forward edge which is slanted backward for the use indicated.

There being recognized advantages in the inclination of windshields, in the minimization of windshield frame elements or door frame elements at the ends of a windshield, and in a corresponding inclination and reduction of window frame elements provided for use adjacent the ends of windshields, it is an object of the present invention, providing a substantially trapezoidal window opening in the upper portion of a car door and employing in said opening a window whose forward edge includes an obtuse angle (a lower guide-engaging portion of said edge and a rear edge of said window being preferably substantially parallel and ordinarily vertical) to provide improved means for at all times so supporting and guiding other portions of the edges of said window as to obviate necessity for so positioning any channel as to engage the extreme upper portion of said forward window edge during completion of an opening movement of said window; and advantageous embodiments of the present invention, in which an extreme upper portion of a forward window edge may even be exposed to view during the completion of such lowering movement, may include, in addition to convergent upper channel elements respectively receiving the rearward edge of said window and the upper portion of said forward edge thereof when said window is closed, a double-arm regulating means connected with the lower edge of said window, and additional channel elements whose bottoms are respectively in constant engagement with the rearward edge of said window and with the lower portion of the forward edge thereof,—the last-mentioned channel element being upwardly so expanded as to provide widening flanges having edges in substantially parallel relationship with the upper portion of said forward edge, in order adequately to support the latter when said window is lowered out of engagement with the corresponding upper channel element.

Other objects of the present invention, including preferred angular relationships and various details of construction of cooperating parts, may be best appreciated from the following description of an illustrative embodiment thereof, taken in connection with the appended claims and the accompanying drawing.

Fig. 1 is an elevational inside view of a door-window organization illustrative of the present invention, parts being broken away from all adjacent parts such as windshield frame or door frame or post elements being omitted.

Fig. 2 is a view comparable with the left-hand portion of Fig. 1, but showing the window of the

illustrated door as approaching its lower limit of motion.

Fig. 3 is a detail sectional view, on an enlarged scale, taken substantially as indicated by the line 3—3 of Fig. 1.

Fig. 4 is a similar sectional view, taken substantially as indicated by the line 4—4 of Fig. 2.

Fig. 5 is a view taken similarly to the views thereabove, but showing an optional variation in the form of the window opening.

Referring first to the more general features shown in Figs. 1—4 inclusive, the door D comprises an outside panel 10 and an inside panel 11, extending substantially parallel with one another and secured together by a Z-section peripheral element 12, of a known type. Panels 10 and 11 are shown as so cut and shaped as to provide a frame for a substantially trapezoidal window opening bordered by a top edge 13, a bottom edge 14, parallel therewith, a rear edge 15, and a forward edge 16,—the latter being shown as downwardly divergent from both the mentioned edge 15 and an inclined edge 17, provided by the upper portion of door D adjacent to a correspondingly inclined windshield frame element or post, not shown.

Movable to and from a position of closure relatively to the mentioned window opening, there is shown a window 18, generally corresponding in configuration with said opening, in that it includes a top edge 13', a bottom edge 14', and a rear edge 15', respectively extending substantially parallel with the corresponding edges of the mentioned opening and adapted to be concealed and supported by said edges, or by channel elements 21 adjacent thereto, when said window is closed. A lower portion of the mentioned door being shown as defined by substantially vertical edges 19 and 20, the forward edge of the window 18 is shown as comprising not only an upper portion 16' parallel with the mentioned edge 16, but a lower portion 20' parallel with the door edge 20 and engageable with the bottom of a special channel element 21 during manipulation of the window 18 by any means adapted to obviate tilting thereof. Opposite and parallel to channel 21 there is shown a cooperating guide channel 22, positioned at all times to receive a portion of the edge 15' of said window; and said edge is shown as perpendicular to edges 13' and 14' thereof.

When in its closed position, the window 18 may be supported by means including not only by an upwardly open channel element 23, movable by some suitable regulator, but also upper channel elements 24 and 25, respectively extending parallel with the rearward edge 15' and with the upper portion 16' of the forward edge of said window; and the lowering and raising of said window may be effected by known means such as a "double-arm" regulator including oppositely ro-

tatable gears 26, 27 supported on pivots 26' and 27'. These gears are shown as manipulable through intermediate gears 31, 32, and 33, operatively connected with one another and with an exposed crank 34,—crank arms 35 and 36 being so secured by pins 26', 27' and additional elements 29 and 30, and so provided with cam studs 37 and 38, entering a lateral groove 39 provided in the channel element 23 as to operate in a known manner.

In preferred embodiments of this invention, although a central portion of the lower edge 14' of the window 18 is secured in the channel 23, terminal portions 14a and 14b of said lower edge are always retained between lateral flanges 40, 40' and 41, 41' of the respective channels 21 and 22; and the channel element 21 is outwardly extended in such manner that the edges of the flanges 40 and 41 extend substantially parallel with the forward edge 16 of the window opening and the upper portions thereof are adapted to receive a considerable portion of the correspondingly inclined upper portion 16' of the forward edge of the window 18 whenever said window is lowered to such a position that the last-mentioned edge is downwardly withdrawn from the cooperating upper channel element 25, extending substantially parallel therewith.

The general mode of operation of all parts of the disclosed organization having been indicated in connection with the description thereof, it is suggested in Fig. 5 that, if desired, although an obtuse angle 42' between the upper portion 16' and the lower portion 20' of a forward window edge may in most or all cases be substantially greater than an angle 42 between corresponding portions 17 and 20 of a door receiving said window, in case it is considered important completely to obviate exposure of the upper portion of a forward window edge incidentally to a raising and/or lowering of the same the forward edge of a window opening may be so modified as to include not only an inclined upper portion 16a but a substantially vertical lower portion 16b,—a corresponding angle 42'' between these parts being preferably similar to an angle 42 or to the more obtuse angle between the upper portion 16' and the lower portion 20' of the forward edge of the window cooperating therewith in door D'; and the upper channels 24, 25 are preferably formed integral with one of the panels 10, 11 or with another part providing a frame for the window.

Although the foregoing description has included details of but one complete embodiment of the present invention, and suggestion of but one alternative form, it should be understood not only that various features of this invention might be independently used but also that numerous additional modifications might easily be devised by skilled workers, if informed of the foregoing,—all without departure from the scope of the present invention, as the latter is indicated above and in the following claims.

What I claim is:

1. In a car door having a window opening and having also a forward edge which includes an angle, an upper portion of said edge being rearwardly inclined: a window having, in addition to substantially parallel top and bottom edges and a rearward edge extending therebetween, a forward edge having therein an angle between upper and lower portions thereof; upwardly convergent upper channel elements respectively receiving said rearward edge and the upper portion 75 of said forward edge when said window is closed;

and means for so supporting and guiding said window, in substantially parallel relationship with the lower portion of said forward edge, as to obviate necessity for support of the upper portion of said forward edge during completion 5 of an opening movement of said window, said window opening being substantially trapezoidal in general outline and at least an upper portion of a forward edge of said opening being substantially parallel with the upper portion of said forward window edge and said means including a guide which provides flanges which upwardly increase in breadth, to afford lateral support for said upper edge portion upon the withdrawal thereof from a first-mentioned channel element. 10 15

2. In a car door having a window opening and having also a forward edge which includes an angle, an upper portion of said edge being rearwardly inclined: a window having, in addition to substantially parallel top and bottom edges and 20 a rearward edge extending therebetween, a forward edge having therein an angle between upper and lower portions thereof; upwardly convergent upper channel elements respectively receiving 25 said rearward edge and the upper portion of said forward edge when said window is closed; and means for so supporting and guiding said window, in substantially parallel relationship with the lower portion of said forward edge, as to obviate necessity for support of the upper portion of said forward edge during completion of an opening movement of said window, said rearward window edge and the lower portion of said forward edge being substantially parallel, and mentioned guide 30 means being provided by additional channel elements, substantially parallel thereto, the sides of one of which are outwardly extended, to provide edges in substantially parallel relationship with the upper portion of said forward window edge. 35

3. A vehicle having sloping pillars at a window opening, a guide channel in the window recess, a glass for closing said opening having an edge cooperating with said channel, a portion of which is of substantially the same slope as the slope of the channel and a portion therebelow which is substantially vertical, a vertically disposed channel positioned below said first channel to guide said vertically disposed edge portion of said glass, the flanges of said channel extending outwardly 45 an amount sufficient to encompass the glass at the sloping portion thereof when lowered. 50

4. A vehicle having sloping pillars at the window opening, a sloping guide channel associated therewith, a glass for enclosing said opening having an edge cooperating with said channel, a portion of which is of substantially the slope of said channel and a portion therebelow substantially vertical, a vertically disposed channel positioned below said first channel to guide the vertically disposed edge portion of said glass, the sides of the channel extending outwardly to constitute sloping edges which encompass the sloping portion of the edge of the glass when lowered to provide lateral support the full length of the glass. 60 65

5. A door for a vehicle provided with a window opening and having a front sloping edge adjacent to said opening, the construction of which door includes a frame and panel elements secured together, a channel disposed between said panels and secured thereto, a window pane for enclosing said opening having a sloping edge substantially conforming to the slope of the position of said channel, and a channel supported on said frame and positioned to guide said window when lowered, the sides of the last said channel being 70 75 80 85 90 95 98 99 100

of varying depth to encompass the entire front edge of the window glass when lowered.

6. In combination, a part provided with a window opening having a side edge portion inclined to the vertical, a window for said opening mounted in said part for vertical movement, whereby said opening can be selectively exposed or closed by said window, said window having its side edge portion adjacent said inclined opening edge portion correspondingly inclined, and a window runway or channel associated with said part for receiving the inclined side edge portion of said window and for guiding and supporting said window edge portion during vertical movement of said window, said runway or channel having a base and a pair of side walls, the side walls of that portion or section of said runway or channel for receiving said inclined window edge portion, when said window is in closing position relative to said opening, being of uniform depth and the side walls of that portion or section of said runway or channel for receiving said inclined window edge portion, when said window is in exposing position relative to said opening, being of varying depth.

7. In combination, a part provided with a window opening having a rearwardly inclined front edge portion, a window for said opening mounted in said part for vertical movement, whereby said opening can be selectively exposed or closed by said window, said window having the front edge portion of its top part rearwardly inclined and the front edge portion of its bottom part generally vertically disposed and a window runway or channel associated with said part for receiving the front edge portions of the top and bottom parts of said window and for supporting and guiding said window front edge portions during vertical movement of said window, said runway or channel having a base and a pair of side walls, the side walls of that portion or section of said runway or channel for receiving the inclined front edge portion of the top part of said window, when said window is in closing position relative to said opening, being of uniform depth and the side walls of that portion or section of said runway or channel for receiving a vertically disposed front edge portion of the bottom part of said window, when said window is in closing position, and for supporting and guiding the inclined front edge portion of the top part of said window when said window is in open position relative to said opening, being of increased depth.

8. In combination, a part provided with a window opening having a side edge portion inclined to the vertical, a window for said opening mounted in said part for vertical movement, whereby said opening can be selectively exposed or closed by said window, said window having its side edge portion adjacent said inclined opening edge portion correspondingly inclined, and a window runway or channel associated with said part for receiving the inclined side edge portion of said window and for guiding and supporting said window edge portion during vertical movement of said window, said runway or channel having a base and a pair of side walls, the side walls of that portion or section of said runway or channel for receiving said inclined window edge portion, when said window is in closing position relative to said opening, being of uniform depth and the side walls of that portion or section of said runway or channel for receiving said inclined window edge portion, when said window is in exposing position relative to said opening, being of varying depth, 75 with the maximum depth thereof appreciably

greater than the depth of the side walls of said first mentioned runway or channel portion or section.

9. In combination, a part provided with a window opening having a side edge portion inclined to the vertical, a window for said opening mounted in said part for vertical movement, whereby said opening can be selectively exposed or closed by said window, said window having its side edge portion adjacent said inclined opening edge portion correspondingly inclined, and a window runway or channel associated with said part and extending along the inclined side edge portion of said opening and below said opening edge portion for receiving the inclined side edge portion of said window and for guiding and supporting said window edge portion during vertical movement of said window, said runway or channel having a base and a pair of side walls, the side walls of that portion or section of said runway or channel arranged along the inclined side edge portion of said opening, for receiving the inclined side edge portion of said window when said window is in closing position relative to said opening, being of uniform depth and the side walls of that portion or section of said runway or channel arranged along the inclined side edge portion of said opening, for receiving the inclined side edge portion of said window when said window is in exposing position relative to said opening, being of increased depth.

10. In combination, a part provided with a window opening having a side edge portion inclined to the vertical, a window for said opening mounted in said part for vertical movement, whereby said opening can be selectively exposed or closed by said window, said window having its side edge portion adjacent said inclined open edge portion correspondingly inclined, and window runway for guiding said window against displacement out of its plane associated with said part for securing the inclined side edge portion of said window and for guiding and supporting said window edge portion during vertical movement of said window, said runway having a pair of side walls, the side walls of that portion or section of said runway for receiving said inclined window edge portion, when said window is in closing position relative to said opening, being of uniform depth and the side walls of that portion or section of said runway for receiving said inclined window edge portion when said window is in exposing position relative to said opening, being of varying depth.

11. In combination, a part provided with a window opening having a side edge portion inclined to the vertical, a window for said opening mounted in said part for substantially vertical movement, whereby said opening can be selectively exposed or closed by said window, said window having its side edge portion adjacent said inclined open edge portion correspondingly inclined, and a pair of window runways for guiding said window against displacement out of its plane and associated with said part for securing the inclined side edge portion of said window and for guiding and supporting said window edge portion during substantially vertical movement of said window, one of said runways at the window opening having the extending sides terminating at the edge thereof, the other of said runways being disposed below the window opening and having its sides extending to project below said opening to provide a channel of greater depth than the channel formed in said first runway.
